CONVERTIBLE CHAIR

Dock Roosevelt Womack, Jr., Raleigh, N. C.

Application February 15, 1946, Serial No. 647,792

2 Claims. (Cl. 155—43)

1

This invention relates to improvements in chairs, and more particularly to a chair having a portion which may be readily converted into a table.

A main object of the invention is to provide a novel and improved convertible chair of simple construction and which is easy to manufacture, said chair having a foldable portion which may be readily extended to form a table.

A further object of the invention is to provide an improved combination chair and table wherein the table portion may be folded into the back of the chair when said table portion is not in use, said table portion being readily extensible when desired and forming a horizontal supporting surface of substantial area.

Further objects and advantages of the invention will become apparent from the following description and claims, and from the accompanying drawings, wherein:

Figure 1 is a rear elevational view of the convertible chair of the present invention, said chair being shown with the table portion thereof in folded position;

Figure 2 is a side elevational view of the chair of Figure 1.

Figure 3 is a vertical cross-sectional view taken through the chair of Figure 1 with the table portion thereof shown in extended position.

Figure 4 is a top plan view of the chair as shown in Figure 3.

Figure 5 is a cross-sectional detail view taken on line 5—5 of Figure 3.

Figure 6 is a cross-sectional detail view taken on line 6—6 of Figure 3.

Referring to the drawings, 11 designates a chair comprising a seat portion 12, a pair of front legs 13, 13 secured to and supporting the forward end of seat portion 12, and a pair of rear post members 14, 14 secured to and supporting the rearward end of said seat portion. Securing the upper portions of rear post members 14, 14 are a pair of vertically spaced horizontal bar members 15 and 16, the lower bar member 16 being spaced a substantial distance above seat portion 12.

The lower portions of rear post members 14, 14 are braced together and secured to front legs 13, 13 by conventional chair rungs 17, and by bar members 18 positioned above the rungs 17. Seat portion 12 is provided with a side drawer 19 in which articles may be stored.

Hinged at 24 to lower horizontal bar member 16 and normally depending therefrom in a substantially vertical position is a table top member

2

20, said table top member comprising a flat table surface 21 having marginal depending side edge elements 22, 22, and a front depending end element 23, defining a cavity with respect to table surface member 21. When the table member 20 is in inoperative position, a portion thereof adjacent the hinges 24 is received in the space between lower horizontal bar 16 and seat portion 12, as shown in Figure 2. To facilitate the folding of table member 20 to this position a pair of notches 25 are formed in side edge depending elements 22, 22 to receive the rearward part of seat portion 12, thus providing more compact nesting of the table member 20 with respect to seat portion 12.

Pivots secured to the inner surfaces of side edge depending elements 22, 22 adjacent the depending end element 23 remote from hinges 24 are supporting leg members 26, 26 adapted to be nested inside table member 20 when said table member is in folded position but movable by gravity to vertical positions when the table member is unfolded to the horizontal position thereof shown in Figures 3 and 4. It will be noted in Figure 1 that the pivotal connections of legs 26 are immediately beneath the table top 20 and that the notches 25 do not extend as far as the under surface of the table top so that, when legs 26 are swung to folded position they lie behind the unnotched part of the depending side elements 22 just above notches 25 and thus avoid interference with the reception of the rear of seat 12 in said notches. Pivots secured to the outer surfaces of side edge depending elements 22, 22 adjacent the points of pivotal securement of leg members 26, 26 are diagonal brace members 27, 27. In the inoperative position of table member 20 brace members 27, 27 are swung to substantially vertical positions adjacent the respective post members 14, 14 and secured to said post members by suitable latches. When table member 20 is in unfolded position, as shown in Figures 3 and 4, the free ends of brace members 27, 27 are secured to the lower portions of the respective post members 14, 14 by removable wing bolts 28, 28 which pass through the ends of the brace members and are threadedly engaged with the post members as shown in detail view in Figure 6. The connections are made just below the adjacent horizontal connecting bar member 18 which connects the post members 14, 14. Brace members 27, 27 are effective to rigidly support table member 20 with respect to chair 11 while leg members 26, 26 resist any tendency for the structure to tip rearwardly when a load

is placed on the table. If desired, suitable locking means may be provided to maintain leg members 26, 26 in vertical position when the table is extended.

While a specific embodiment of a convertible chair structure has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A convertible chair comprising a pair of spaced legs, a pair of spaced posts arranged in opposed aligned relation with respect to said legs, a seat having one end supported on said legs and having the other end secured to said posts, a horizontally-disposed bar interposed between said posts and secured to the latter, said bar being positioned above and spaced from said seat, a table member having one end pivotally connected to said bar for movement from an upright depending position to a horizontal position projecting rearwardly of said posts, a leg positioned on each corner of said table member adjacent the other end of the latter and having one end pivotally connected to the adjacent side edge of said table member for movement from a horizontal position in parallel relation with respect to said table member to a vertical position parallel with respect to said posts, a brace member positioned on each corner of said table member adjacent the other end of the latter and having one end pivotally connected to the adjacent side edge of said table member for movement from a horizontal position in parallel relation with respect to said table member to a position extending between said table member and a post adjacent thereto, and means on the other end of each of said brace members for detachably securing the latter when in extended position to the adjacent posts.

2. A convertible chair comprising a pair of spaced legs, a pair of spaced posts arranged in opposed aligned relation with respect to said legs,

4
a seat having one end supported on said legs and having the other end secured to said posts, a horizontally-disposed bar interposed between said posts and secured to the latter, said bar being positioned above and spaced from said seat, a table member embodying a top and side elements depending from said top, said table member having the top adjacent one end pivotally connected to said bar for movement from an upright depending position to a horizontal position projecting rearwardly of said posts, a leg positioned on each corner of said table member adjacent the other end of the latter and having one end pivotally connected to the inner face of the adjacent side element of said table member for movement from a horizontal position in parallel relation with respect to said table member to a vertical position parallel with respect to said posts, a brace member positioned on each corner of said table member adjacent the other end of the latter and having one end pivotally connected to the outer face of the adjacent side element of said table member for movement from a horizontal position in parallel relation with respect to said table member to a position extending between said table member and a post adjacent thereto, said side elements being provided with aligned notches for accommodating the adjacent portion of said seat when the table member is in its upright depending position, and means on the other end of each of said brace members for detachably securing the latter when in extended position to the adjacent posts.

DOCK WOMOCK, JR.
